UNITED STATES PATENT OFFICE.

FREDERICK B. CASMIRE, OF CHANUTE, KANSAS.

MOP.

1,420,180.

Specification of Letters Patent. Patented June 20, 1922.

Application filed April 3, 1920. Serial No. 371,003.

To all whom it may concern:

Be it known that I, FREDERICK B. CASMIRE, a citizen of the United States, residing at Chanute, in the county of Neosho and 5 State of Kansas, have invented a certain new and useful Improvement in Mops, of which the following is a specification.

My invention relates to improvements in mops.

10 The object of my invention is to provide a mop with which the corners of a room may be easily and thoroughly cleaned, which is simple in construction, which is cheap to manufacture, is durable, and not 15 liable to get out of order and which is easy to operate.

A further object of my invention is to provide in a mop of the type having a casing and a supporting frame of novel and 20 simple means for attaching the casing to a supporting frame which is attached to a handle, which attaching means permits of the easy and quick mounting of the casing on the frame or of its removal therefrom 25 for laundering purposes, and which fastening means dispenses with the use of buttons, laces or similar securing means.

The novel features of my invention are hereinafter fully described and claimed.

30 In the accompanying drawings, which illustrate the preferred embodiment of my invention,

Fig. 1 is a perspective view of my improved mop shown in operative position in 35 the corner of a room.

Fig. 2 is an enlarged horizontal sectional view of the same.

Fig. 3 is a perspective view of the 40 casing with the shag removed.

Fig. 4 is a cross section on the line 4—4 of Fig. 2.

Similar reference characters designate 45 similar parts in the different views.

1 designates the body of a frame, preferably resilient wire, the body being, preferably, substantially triangular and having 50 at its rear side two end portions 2, normally spaced apart and preferably provided with laterally extending corrugations 3, which

body 1 and a handle 4, to which the extensions 2 are attached.

Opposite sides of the handle 4 at its forward end may be grooved for the reception of the extensions 2. Said extensions have 55 inwardly turned ends 5, Fig. 2, which extend into a transverse hole 6 in the handle 4.

A ferrule 7 embraces the handle 4 and the extensions 2. A securing device, such as a nail or screw 8 extends through the ferrule 60 7 into the handle 4 to hold the ferrule in place.

Fitted over the frame 1 is a substantially triangular casing 9 having at its rear end 10 an opening 11 of less length than the 65 width of the end 10. The rear end of the frame 1 normally extends outwardly beyond the ends of the opening 11, whereby the casing 9 is firmly retained on the frame 1. The resilient frame 1 is compressible, by 70 squeezing toward each other the corrugated portions 3, to a position, in which the frame 1 may be withdrawn or inserted through the opening 11.

By having the extensions 2 of substantial 75 length, such contraction of the frame 1 may be easily effected, and the handle being rigid, 4 may be retained in the angular position shown in Fig. 1, while the casing 9 is 80 in a horizontal position.

The casing 9 is preferably provided with a shag 12 which covers the upper and lower sides of the casing.

The forward end of the casing 9 has attached to it a wedge-shaped block 13, preferably formed of layers of fabric, with which corners may be easily and thoroughly cleaned.

By having the shag on both sides of the casing and having extensions 2 flexible, 90 either side of the casing may be disposed upwardly while the handle 4 is in the inclined position shown in Fig. 1.

When it is desired to launder the casing, it may be readily removed from the frame 1 95 by squeezing together the extension 2 to a position in which the frame will pass through the opening 11.

I do not limit my invention to the structure shown and described, as many modi- 100

fications, within the scope of the appended claim, may be made without departing from the spirit of my invention.

What I claim is:—

- 5 In a mop, a frame of resilient wire formed into a substantially triangular body having its end portions directed away from the body to provide means for attaching a handle, and a casing in which the body is fitted hav-

ing a substantially triangular relatively thick front end portion comprising laminations of fabric fastened together, the casing having a shag on opposite sides thereof, substantially as set forth.

In testimony whereof I have signed my name to this specification.

FREDERICK B. CASMIRE.
